UNITED STATES PATENT OFFICE.

HARRY S. WILLIAMS, OF SAN ANTONIO, TEXAS.

SANITARY NAPKIN.

Application filed August 30, 1926. Serial No. 132,541.

This invention relates to sanitary napkins for women's use and a primary object thereof is to provide a napkin of this character with a waterproof filler or inner liner to 5 avoid all danger of soiling the clothing of the wearer and yet provide a device which is comfortable and will not chafe the user.

Another object is to so construct this napkin that while it may be cheaply manufactured, it will afford the protection required 10 of such a garment.

In carrying out these objects, the invention is susceptible of modification without departing from the spirit or sacrificing any 15 of the advantages of the claimed invention, there being shown in the drawing for illustrative purposes a preferred and practical form in which:—

Fig. 1 represents a perspective view of 20 the completed article embodying this invention in the shape in which it is placed on the market.

Fig. 2 is a similar view showing the outer covering or envelope partially open to 25 disclose the interior construction, the absorbent layers being shown broken away to more clearly disclose the inner liner or filler.

Fig. 3 is a longitudinal section through 30 the completed article.

Fig. 4 is a transverse section taken on the line 4—4 of Fig. 3; and

Fig. 5 is a perspective view showing a slightly different form of the invention.

Similar reference characters indicate 35 corresponding parts in all the figures.

In the embodiment illustrated in Figs. 1 to 4, the body of the napkin 1 may be composed of any suitable absorbent material such as cotton layers, paper in sheet form or 10 any other cheap absorbent material. As shown, this napkin body is composed of a plurality of layers or plies 2, any desired number of which may be employed to produce the necessary thickness, a waterproof 15 inner liner or filler 3 being arranged near the bottom of said body between the plies thereof of over which are arranged one or more of said plies to absorb any fluid which may pass around the edges of the filler. The side edges 20 of the absorbent layers or plies preferably extend beyond the side edges of the filler as shown at 4 in Fig. 4 to avoid all possibility of the edges of the filler chafing the skin of the user. This filler or inner liner 3 may be 25 composed of any suitable waterproof sheet

material such as rubberized cloth, sheet rubber, oil cloth, oil silk or paraffin treated fabric, the requirements necessary being that it shall be impervious to fluid.

This inner liner or filler 3 is placed between the plies or layers of absorbent fabric near the bottom of the article and the ends thereof extend beyond the ends of the layers and are turned inwardly as shown at 5 and covered by other layers and secured to the 60 body by any suitable means, glue 6 being here shown for this purpose.

This pad 1 is designed to be encased in a cheese-cloth or any suitable envelope or cover 7 which is shown in the form of a 70 rectangular sheet having the edges 8 thereof lapping when in operative position, the double or multiple ply ends 9 thereof being foldable one over the other as shown in Fig. 1 when the pads are to be packed in a suitable container and these ends are designed to be open out and used as attaching elements for securing the pad in operative 75 position when in use.

The gist of the invention resides in the arrangement of a waterproof inner liner in an absorbent pad of this character and so locating it as to prevent all possibility of fluid passing through or beyond the edges 80 of the pad.

In the form shown in Fig. 5, the construction is exactly the same as that shown in the other figures except that the corners of the pad are rounded as shown at 10 to render 85 the device more comfortable and to prevent the corners from catching in clothing.

While the details disclosed may be considered as preferred, it is to be understood that within the scope of the claimed invention, variations may be made.

I claim:—

A sanitary napkin comprising a main absorptive pad formed of a multiplicity of plies, a liquid-proof fluid-spreading strip of less width than said pad, said strip extending along the lower side of the pad and having its ends turned inwardly upon and secured to the pad ends, the longitudinal edges of said strip being inwardly spaced from those of the pad to prevent chafing of the wearer by said edges, an auxiliary relatively thin pad formed of a plurality of plies, said auxiliary pad lying against the lower side of and being secured at its ends to said strip, said auxiliary pad being of the same 100 105 110

length and width as said main pad, whereby the longitudinal edge portions of said auxiliary pad project beyond the longitudinal edges of said strip to absorb any fluid which 5 may creep around said edges, and a relatively few plies of absorptive material lying upon said main pad and said inturned ends

of said strip and secured to the latter, the last named plies preventing chafing of the wearer by said inturned strip ends.

In testimony whereof I have hereunto fixed my signature.

HARRY S. WILLIAMS.
